UNITED STATES PATENT OFFICE.

NICHOLAS SHANNON, OF PANAMA, ILLINOIS, ASSIGNOR TO LINK BELT COMPANY, OF CHICAGO, ILLINOIS, A CORPORATION OF ILLINOIS.

PROCESS OF WASHING COAL AND SEPARATING REFUSE THEREFROM.

1,190,960.

Specification of Letters Patent.

Patented July 11, 1916.

Application filed May 22, 1908. Serial No. 434,428.

To all whom it may concern:

Be it known that I, NICHOLAS SHANNON, a citizen of the United States, and resident of Panama, Montgomery county, Illinois, 5 have invented certain new and useful Improvements in Processes of Washing Coal and Separating Refuse Therefrom, of which the following is a specification containing a full, clear, and exact description, reference 10 being had to the accompanying drawings, forming a part hereof.

My invention relates to a process of washing coal and separating refuse therefrom, and the object of my invention is to contribute to the art a process wherein coal is 15 submerged and by a jiggling action subjected to the action of a series of jets of water which are automatically controlled by a self-maintained bed of refuse from the coal, as maintained bed of refuse from the coal, as 20 will be hereinafter pointed out.

I accomplish the cleaning and separating operations by subjecting a continuously moving body of coal and refuse to the action of a series of jets of water of varying pressure, which action takes place on the down 25 stroke of the jig, or like member, through which the body of coal and refuse moves, and said body of coal and refuse being subjected to a washing and settling action of 30 the water through the body of coal and refuse.

In order that my process may be more readily understood, I have shown in the accompanying drawing a simple structure, 35 particularly adapted for carrying out my process, although it will be understood that said process may be accomplished in a variety of ways.

The figure shown in the drawing is a 40 vertical section taken through the center of a tank and jig; and, referring by numerals to this drawing, 1 designates the tank, which is divided by vertically disposed partitions 2 and 3 into three compartments, A, B and 45 C, the compartment A being the cleaned coal compartment, the compartment B the jig compartment, and C the refuse compartment.

Arranged for vertical reciprocation in the 50 compartment B is a vertically disposed jig 4, preferably provided with antifriction rollers 4^a, which bear against the partitions 2 and 3 to minimize the necessary power for the vertical movement of the jig; 55 and rigidly fixed in the upper portion of

this jig 4 is a perforated plate 5, at or near one end of which is formed an opening 6.

Arranged on the plate 5, immediately adjacent the opening 6, is a vertically disposed wall 7, in the lower portion of which is formed an opening 8, which is adapted to be closed by a vertically moving gate 9, which is connected to an adjustable hand lever 10 arranged on the upper portion of the jig. 60

Extending laterally from the upper portion of the jig 4 and from the upper end of the wall 7 immediately over the partition 2, is a cleaned coal spout 11, provided with side walls, and which spout is slightly inclined from its outer end toward the wall 7. 70

Fixed to the upper portion of the jig, directly opposite this spout 11 and immediately over the inclined upper end of the perforated plate 5, is a hopper 12, through 75 which the coal to be cleaned is delivered.

The body of the jig beneath the perforated plate 5 is for the sole purpose of providing means for conserving and directing water pressures created by movements of 80 the jig to act on the coal and its refuse.

In carrying out my process with the structure shown, the jig 4 is vertically reciprocated in any suitable manner and the coal to be washed is continuously delivered into 85 the hopper 12; and said coal passes from thence downward onto the upper end of the inclined perforated plate.

It is to be distinctly understood that coal and its refuse from the time of their delivery 90 to the jig, during the jiggling actions and during their discharge from the jig, are wholly submerged.

The jig is vertically reciprocated and in its downward movement the operation of 95 the jig beneath the perforated plate provides a rise in pressure of the water therein contained, thus impelling it through the perforations and causing it to issue into the mass of coal and refuse in jets of sufficient 100 force to elevate the coal and refuse above the plate. Owing to the difference in specific gravities of the coal and its refuse a separating and stratifying action takes place. 105

The gate 9 is open to such a degree as desired by means of the adjustable handle 10; and the continuously moving body of refuse, after passing beneath the gate 9, will discharge through the opening 8, and from 110

thence downward through the opening 6, and will finally pass into the lower portion of the compartment C, from whence it may be removed.

5 The openings or perforations in the plate are of such size as to prevent a material discharge of refuse therethrough so that a bed of the refuse will be continuously maintained upon the plate.

10 By the provision of a controllably sized outlet for the discharge of refuse at a point where it is subjected to the varying water pressures, created by the movement of the jig body, beneath a plate and at a point remote from the supply, I am enabled to control the layer or bed of refuse on the plate as to character, quantity and disposition.

15 The removal of the refuse from the machine takes place through a compartment of the tank in communication with the jigging or process compartment only at its lowermost end, so that the removal may be effected during the operation of the process with a minimum of contamination and disturbance of the water in the process compartment.

20 In addition to the advantage just set forth in the provision of a compartment partially separated from the process compartment I find the said refuse compartment acts as a water column communicating with the water-confining chamber comprising the lower part of the jig.

25 By virtue of the jigging element being separated from the wall of the jigging compartment there exists a continuous and circuitous passage way through the bed of material to be acted upon, and including the space surrounding the jigging element, in order that a water circulation may be maintained therein, whenever the jig is in operation.

30 During the reciprocating motions of the jig the body of refuse carried thereby has a sort of valve-like action; it being, during the downward excursion of the jig, lifted or held somewhat in suspension by the water pressure generated in the compressed chamber and acting thereon, permitting a relatively free flow of water through the plate 5 and the said body of refuse. During the reverse excursion of the jig the body of refuse descends, resting heavily upon the plate 5 and obstructing the flow of water through the jet openings in the said plate. The general course or direction of the flow of water is therefore in a direction upward through the jig, whence it passes outward, some flowing through the delivery spout 60 with the coal, and the balance, over the top of the jig, and thence downward through the space between the jigging element and the wall of the compartment in which it operates, and from thence back into the 65 compression chamber of the jig. It will be

noticed that in this circulation system there is a point where the coal and water are discharged through a spout.

70 The coal, on account of the size and weight of the particles thereof, falls abruptly into a relatively stagnant portion of the body of water, while the lighter floating particles of refuse which pass over the top edge of the jig are carried along with the more active circulating stream. Furthermore, it will be 75 noticed that the passage way between the jigging element and the wall of the jigging compartment is of lesser area than the space immediately beneath the jig. In consequence of this relationship of areas the 80 velocity of this circulating stream is greater just prior to the influx of water into the compression chamber than it is before making its turn into the compression chamber. The effect in this change in velocities is that 85 the particles of refuse are carried to the bottom of the jigging compartment B, from whence they go into the refuse compartment C and are thereby separated from the circulating stream which, freed from said refuse, continues its cycle of washing operation. 90

95 It is to be observed that in the present embodiment of my invention there is a chamber for securing high and low pressures alternately. In communication with this chamber there is a multiplicity of jets decreasing in activity with the trend of travel of material in the jigging element above the said chamber. It is to be observed further that there is a port, namely, the refuse discharge opening, communicating with the same chamber as the said jets, affording stream lines at substantially right angles to the flow of the jets, both jets and port stream varying their flow proportionately with the 100 alternations of pressure in the chamber so as to produce whirls in the wash water by eddy currents and, alternately with these whirls, a motion toward the discharge end, these two different alternate actions being 105 brought about by the valve-like action of the refuse. 110

115 Water flowing through the jet openings moves substantially at right angles to the trend of material, while the water flowing through the port or discharge opening moves substantially parallel with the trend of the material. The effect of these two streams of fluid impinging upon each other at any considerable angle is to produce a whirl or eddy current. The purpose of the eddy current, thus established, is to produce a scouring action upon the material within the jig, to assist in freeing the jet openings in the plate 5 from refuse, and to loosen the bed or stratum of refuse, especially the portion thereof adjacent to the discharge opening. It will be understood that, since the discharge opening for the refuse leads directly into the compartment confining the body of water in 120 125 130

which the jig reciprocates, there is no tendency for the water, on the downward excursion of the jig, to flow across or short-circuit through the body of refuse, from the 5 jet holes in the plate 5 to the refuse discharge opening 8, as would be the case should the said opening deliver outside the said confined body of water; for the inward moving stream of water flowing into the 10 jig through the discharge opening 8 momentarily checks the discharge of the refuse, lifting it and stirring it up, as has been described, while, on the return or upward reciprocation of the jig there is a discharge of 15 the refuse through the said opening.

The water column, which has already been described, is in the refuse compartment C and communicates with the jig or process compartment by a throat at the bottom of 20 said compartments, operates to dampen or control the alternate pressures to a certain extent in the jet apparatus or jig. The said throat is so proportioned as to cause the desired activity of the jet flow, but it should 25 be never less than a capacity sufficient for the free exit of refuse.

By subjecting coal and its refuse to jets of water under relatively high pressure at the place in the apparatus where the coal is 30 delivered thereto, there is obtained not only a powerful washing action but a wide degree of separation between the coal and the refuse washed therefrom.

By gradually diminishing the force of 35 the jets from the receiving end of the apparatus to the delivery end and obtaining a relatively slight jet action at the delivery end, the coal is continuously subjected to a washing action without danger of discharging 40 refuse with the coal at the delivery end. This graduated jet pressure is brought about by a self-maintained and uniform bed of refuse material of gradually increasing thickness from the receiving to the delivery 45 end of the jig.

In the case of removing fine dust or dirt from coal where the percentage of refuse is small, the discharge gate is closed and the bed of refuse already formed operates in 50 exactly the same manner as above described, the particles of refuse, however, being light are carried out by the circulating stream of water, in a course already indicated, and over the top of the jig. The heavier lumps 55 of coal on arriving at the end of the spout drop to the stagnant part of the body of water beneath, while the lighter particles of dirt to be removed from the jig are carried by the more active stream of water along 60 the general line of circulation.

As the water of the stream descends between the side of the jig and the wall of the jiggling compartment it makes an abrupt turn at the bottom of this passage way. As 65 has already been explained a difference in

velocity occurring here permits the water to return into the pressure chamber of the jig, which is in the course of flow of the circulating water, while the particles of refuse that have been separated continue their vertical course downward through the throat into the refuse compartment.

It will be seen that the material being treated is moved laterally or horizontally in a comparatively thin layer, and while moving, as a mass, is subjected to up and down movements beneath the surface of a confined body of still water, as distinguished from a flowing stream of water. The effect of this action upon the material is to separate 80 it into strata, as has been described, the lighter, and, when coal is being treated, the valuable, material, constituting the upper stratum, and the refuse material, the lower stratum. These two bodies of material are 85 delivered out of the machine at different levels, the lighter material being discharged outside of the jig and the compartment in which it operates, while the heavier refuse material is discharged into the body of water confined in said compartment, whereby 90 inequality of action and irregularity of stream movement in the water which is being utilized to stratify the material and loosen the bed of material, is obviated.

The process and apparatus described insures the maintenance of a uniform bed of refuse material during the operation of the apparatus, the discharge of the refuse being substantially uniform or continuous, and 100 not tending to disturb the uniform characteristics of the refuse bed, as is the case in the operation of those forms of apparatus where are employed discharge gates or valves that are intermittently opened to a 105 considerable extent or for a considerable time, permitting the discharge of the accumulated refuse, after which they are closed, allowing refuse to accumulate.

By causing the jig to operate in a confined 110 body of water, and discharging the refuse into this body, short-circuiting of the streams of water from the jet openings in the supporting plate to the refuse discharge opening,—with the incident rapid washing out 115 of the refuse material on the down movements of the jig and the consequent breaking down or disturbance of the uniform and continuous layer of refuse material,—is prevented, as has already been pointed out. 120 By subjecting the bed of refuse at its discharge end, and the layer of coal thereon as well, to the action of counter water currents, some entering through the openings in the supporting plate 5 and others through the 125 port where the refuse discharges, the material being treated is not only loosened up, as has been pointed out, but the discharge, both of the cleaned coal and the refuse, is facilitated, the lifting and loosening of the 130

- material on the down stroke of the jig resulting in the discharge of the cleaned coal and the settling back of the refuse material on the up stroke of the jig, resulting in the discharge of the refuse.
- Coal washers may be roughly divided into three classes: those which contain fixed jigs through which the water is forced; those which contain reciprocating jigs which are operated in or against a continuously moving stream of water; and those which have jigs reciprocating in still water, that is beneath the surface of a body of relatively still water, and in which the coal and refuse matter are continuously submerged beneath the surface of such body of water. These three classes will include most if not all coal washers. The washer of this application is in the third class. The material to be separated or washed is moved laterally or horizontally in a comparatively thin layer through and substantially beneath the surface of the body of still water. The lateral motion is due to the pressure of the oncoming stream of material. The separation is effected by gravity, for the problem deals with materials of differing specific gravity which have been mixed together. To effect this separation the moving mass of material is loosened by reciprocating it vertically, as it passes along, against a confined body of water, all of the upwardly moving streams, from which the confined body of water is directed upwardly through the moving mass, being substantially uniformly distributed therethrough. As the mass moves under these conditions it is separated into two layers of unequal specific gravity, the lighter being discharged outside of the jig and the jig tank, while the heavier is discharged into the confined body of water whereby disturbances, inequality of action and irregularity of stream movement in the water which is being utilized to loosen the bed are obviated.
- The compartment B may be called the inertia chamber. It is a downwardly extended compartment about the lower end of the jig, and it confines a mass of water which is adapted to be forced upwardly through the coal, or, to put it another way, is adapted when the jig descends to permit the coal to separate by gravity as it tends to fall through so much of the water of such inertia chamber as enters the jig when the jig so descends.
- During the operation the water in the inertia chamber and in the jig may be thought of as for the most part substantially at rest. The water in the inertia chamber does not

flow upwardly in any quantity, but only passes through the perforations in the bottom of the jig while such perforated bottom is descending through the water. Thus a large amount of water is in the jig or above the bottom of the jig and therefore the strata can distribute themselves widely, measured in a vertical direction. In other words, its particles separate or settle or tend to stratify, the lighter on top and the heavier toward the bottom. It is essential for successful operation that substantially all of the water in the jig be confined or be protected from violent lateral displacement. Such lateral displacement would occur if the slate or refuse chamber did not open into the inertia chamber or if it were open at the top. When the jig descends, the entire volume of water within the jig and within the inertia chamber remains practically still except so far as its operation is disturbed by the upward and lateral rush of water through the slate chamber into the jig. When the jig descends, the support for the material within the jig is removed and the particles of the material within the jig being held in suspension immediately begin to descend with unequal velocity according to their specific gravity and arrange themselves in the desired specified form.

I claim:—

The process of separating mixed materials of different specific gravity which consists in moving the same laterally underneath the surface of a confined body of still water in a continuous stream by means of the pressure of the oncoming current of material, reciprocating said moving stream of material vertically beneath the surface of such body of water and against a portion thereof confined in an inertia chamber to permit the stratification of material, discharging the light material from above at the end of the stream into one compartment containing a portion of such still water, the fine heavy material into the inertia compartment below, and the coarse heavy material from below at the end of the stream into an upwardly inclosed body of water and thence into the inertia chamber body of water.

In testimony whereof, I have signed my name to this specification, in presence of two subscribing witnesses.

NICHOLAS SHANNON.
